TRANSFER MECHANISM FOR FURNACES

Harry J. Kuhlman, Detroit, Mich., assignor to
Holcroft and Company, Detroit, Mich., a cor-
poration of Michigan

Application May 19, 1932. Serial No. 612,293

7 Claims. (Cl. 263—6)

This invention relates to transfer mechanism for use with a heat treating furnace or the like. In heat treating crank shafts or other articles of similar nature it is usually customary to push the cranks through a furnace and heat the same to a relatively high degree of temperature then quench the cranks in a bath of oil and then push the cranks through another furnace in which the temperature is considerably lower than that of the first furnace to thereby give the proper qualities to the metal. It is also usual to have one furnace positioned above the other in order to conserve floor space so that it is necessary to lift the articles being heat treated from the end of the lower furnace to the adjacent end of the upper furnace and inasmuch as some of these articles are extremely heavy it requires the services of two men to perform this transfer operation.

It is therefore an object of this invention to provide a transfer mechanism that is practically automatic in operation and which will lift articles from the lower furnace to the upper furnace and which will automatically move the articles through the upper furnace.

Another object of the invention resides in the provision of a transfer mechanism which will keep the carriers on which the articles to be heat treated are positioned moving in an endless line through both the upper and the lower furnaces thereby preventing cooling of the carriers and consequent saving of heat units in the furnace.

Another object of the invention resides in the combination of pusher and elevator means for maintaining a continuous movement of articles to be heat treated through the heating compartments.

A still further object of the invention resides in the provision of pusher means positioned at one end of the lower furnace for continuously moving the articles through the lower heating compartment and elevator means for raising the articles from the unloading end of the lower heating compartment to the loading end of the upper heating compartment for moving the articles in a continuous line therethrough to the unloading end thereof, and elevator means at the unloading end thereof for lowering the carriers from the unloading end of the upper heating compartment to the loading end of the lower heating compartment.

Another object of the invention resides in the provision of means for quickly and automatically withdrawing the heat treated article and carrier block therefor which is closest to the unloading end of the lower furnace to the elevator thereby preventing cooling of the heated article which would occur if the article were withdrawn from the furnace at the same rate of speed at which it travels through the furnace.

These objects and the several novel features of the invention are hereinafter more fully described and claimed and the preferred form of construction by which these objects are attained is shown in the accompanying drawings in 65

Fig. 1 is a sectional view through a furnace equipped with my improved transfer mechanism.

Fig. 2 is a section taken on line 2—2 of Fig. 1. 70

Fig. 3 is a section taken on line 3—3 of Fig. 1.

Fig. 4 is a section taken on line 4—4 of Fig. 3.

Fig. 5 is an enlarged detail sectional view of a

pair of guide rails, carriers and crank shaft.

Fig. 6 is a section taken on line 6—6 of Fig. 1. 75

Fig. 7 is an enlarged detail plan view of the holding pawl.

Referring to the drawings, the furnace 1 comprises the upper heating compartment 2 and the lower heating compartment 3 each being open at 80 their opposite ends as best shown in Fig. 1 to permit loading and unloading of articles therefrom. The rails 4 are positioned on the bottom of the heating chamber 3 while the guide rails 5 are positioned on the bottom of the heating chamber 85 2. It will be understood that suitable heating elements (not shown) are installed in the recesses 6 below the rails. The heating compartment 3 has the inwardly swinging door 7 positioned adjacent the loading end thereof and has 90 the outwardly swinging door 8' positioned adjacent the discharge end. If desired similar doors 9' and 10' may be provided for the upper heating compartment 2. A pusher mechanism 8 is positioned adjacent the loading end of the heating 95 compartment 3 and may be of any desired construction for intermittently shoving the carrier blocks 9 through the furnace.

The carriers 9 are designed to support a crank shaft 11' but it will be understood that articles 100 of various types may be placed thereon without departing from the spirit of the invention. By referring to Fig. 2, it will be seen that there are four rails in each heating compartment arranged in pairs and that the crank shaft is supported by 105 the carriers 9 guided in one pair of rails and as best shown in Fig. 5 each furnace compartment as shown provides for the advance of two rows of work units in parallel. It will be understood that in operation of the pusher mechanism 8 that 110 the reciprocating member 10 will move the carriers 9 toward the heating compartment 3 and will then move back to the position shown in Fig. 1 for engaging behind another set of carriers. It will thus be seen that the entire length of the 115 heating compartments 3 and 2 will be filled with the carriers 9. The ends of the rails 4 stop short of the discharge end of the heating compartment 3 and the rail sections 11 are of similar cross sectional shape and are in longitudinal alignment 120

therewith. The sections 11 are each formed with an inturned end 12 for engaging behind the T shaped extension 13 on the member 14 the same having the guide sections 15 suitably secured thereto and in longitudinal alignment with each of the rail sections 11. The opposite end of the member 13 is formed with the vertically extending T shaped slot 16 which engages the T shaped extension 17 formed on the cross bar 18 the same having the racks 19 secured to each end thereof each rack being engaged by a pinion 20 mounted upon a shaft 21 carried in the bearings 22 and rotatable from suitable mechanism (not shown) through the drive pulley 23.

15 The elevator 24 is formed with the longitudinally extending guides 25 which correctly position the members 14 relatively to the rail sections 11. The elevator 24 is apertured to receive the reduced ends 26 of the threaded rods 27 and is 20 further provided with the apertures 28 which slidably engage the guide rods 29. The rods 29 are suitably secured at their lower ends to the floor and at their upper ends to the framework extending from the end wall of the furnace. The 25 gears or sprockets 30 threadedly engage the rods 27 and are suitably rotated by a chain or gears (not shown). The supporting bars 31 are secured at their outer ends to the framework 32 the same being suitably secured to the floor and the bars 30 are slidably engaged by the cross bar 18 and extend under the members 14 to support the weight of the same when the cross bar 18 is moved outwardly in the direction of the arrow shown in Fig. 3. Each of the pusher blocks 9 is formed 35 with a notch 32 which is engaged by the beveled pawl 33 secured to the arm 34 the same being pivotally mounted at 35 to the elevator 24. A spring 36 abuts the arm 34 and the opposite end abuts the standard 37 the same also being suitably secured to the elevator 24. A roller 38 is pivotally mounted between the ears 39 extending from the bar 34 and is adapted to engage the vertically extending rail 40 the same having a flared lower end 41, for a purpose to be hereinafter described.

45 A pusher mechanism 42 is suitably mounted upon the top wall of the furnace and adjacent the loading end of the heating compartment 2 and comprises the link 43 pivotally secured to the crank 44 the same being rotated through suitable mechanism indicated generally at 45. An arm 46 is pivotally secured to the link 43 and is pivotally secured at 47 to the bracket 48 extending from the end wall of the furnace. The lower end of the arm 46 has one end of the link 49 pivotally secured thereto the opposite end being pivotally secured to the cross bar 50 slidably upon the rods 51 carried by the framework 52 and the end wall of the furnace. An elevator 53 which is similar in construction to the elevator 24 is positioned adjacent the unloading or discharging of the heating compartment 2 and is arranged to lower the carriers 9 from the rails 5 in the upper heating compartment 2 to longitudinal alignment with the rails 4 in the lower heating compartment 3.

70 The operation of the device is as follows: Assuming that both the upper and lower heating compartments are loaded with the carriers 9 upon operation of the pusher mechanism 8 the carrier 9 on which a crank shaft has been placed will be moved along the rails 4 toward the heating chamber 3 and will consequently move all of the carriers along a predetermined distance and will 75 move the carrier 9 adjacent the unloading end of

the heating compartment 3 onto the rail sections 11.

80 Suitable mechanism (not shown) will rotate the pinions 20 and will move the racks 19 in the direction of the arrow shown in Fig. 3 and will move the cross bar 18 in the same direction and the cross bar will pull the members 14 and the rail sections 11 also in the same direction until the carrier on the rail sections 11 is positioned over the elevator 24. The pinion gears 20 will then be rotated in the opposite direction and will move the rail sections 11 back to the position shown in Fig. 1. The pawls 33 will engage in the notches 32 in the carriers 9 which are positioned over the elevator and will prevent return of the same and inasmuch as the rails 15 of the members 14 align with the rail sections 11 the same will engage the flanges of the carriers 9. The elevator 24 will then be raised by rotating the sprocket 30 and the same will move up until the rails 15 come in longitudinal alignment with the rails 5 in the upper heating compartment 2. It will be seen therefore that as the elevator is lifted that the roller 38 will engage the flared end 41 of the rail 40 and will move the pawl 33 90 out of engagement with the notch 32.

95 When the elevator has reached its upper limit of travel the pusher mechanism 42 will come into operation and the pusher head 50 will engage behind the carriers 9 and move the same onto 100 the guide rails in the upper heating compartment 2 and since the carriers are in end to end relation in the upper heating compartment the one adjacent the discharge or unloading end thereof will be moved onto the elevator 53 and 105 the elevator then lowered. The crank that is 110 on the carrier will then be removed and a new one placed thereon and the pusher mechanism 8 will then be put in operation to perform another cycle of operation as heretofore described.

115 It will be noted that the elevator 24 may be raised and lowered as the T shaped extensions 13 will slide by the inturned ends 12 and the T shaped grooves 16 will slide by the T shaped extensions 17 and when lowered the parts will 120 again assume the position shown in Fig. 3 to permit withdrawal of the sections 11 from the furnace.

125 It will be understood, of course, that the different steps in the operation will be so timed by suitable mechanism (not shown) as to be put in operation at the correct instant. It will be further noted that movement of the racks 19 will be relatively rapid so that the carrier on the rail section 11 will be quickly withdrawn 130 from the furnace to prevent cooling of the heat treated article. It will be understood that any number of rails may be used in the furnace without departing from the spirit of the invention.

135 It is the usual practice in treating crank shafts or the like to quench the cranks in a bath of oil after they are passed through the first heating compartment and prior to putting them through the second heating compartment. This particular step, however, forms no part of this invention as the principal object is to keep a continuous line of carriers intermittently moving through the two heating compartments. It will be seen that the carriers have very little chance 140 to cool as they are moved from one heating compartment to the other thereby effecting a saving in heat units that would ordinarily be required to raise the temperature of the carriers to the temperature of the furnace. It will be 145 150

understood, of course, that when the elevator 24 has reached its highest point and the carriers thereon moved into the upper heating compartment that the elevator will immediately lower 5 to a position to receive the next set of carriers from the lower heating compartment and during this downward movement the rollers 38 will pass out of contact with the rail 40 to permit the pawl 33 to be in position to hold the next 10 carriers 9 that are positioned on the elevator.

From the foregoing description it becomes evident that I have provided a transfer mechanism for furnaces that is simple and efficient in operation and which will materially reduce the 15 amount of manual labor required in operation of the furnace.

Having thus fully described my invention, its utility and mode of operation, what I claim and desire to secure by Letters Patent of the United 20 States is—

1. The combination with a furnace having two heating compartments, one positioned above the other, of a plurality of carriers for supporting articles thereon, means in each compartment for guiding the carriers therethrough, means at one 25 end of the lower heating compartment for moving the carriers therethrough, elevating means at the opposite end of the lower heating compartment for raising the carriers to a position in longitudinal alignment with the guide means in the upper heating compartment, and means 30 for moving the carriers from the elevating means through the upper heating compartment and along the guide therein, and means adjacent the opposite end of the upper heating compartment for lowering the carriers to a position in longitudinal alignment with the guide means in the lower heating compartment.
2. A transfer mechanism for a furnace having an upper and lower heating compartment, comprising a movable section positioned in the lower furnace and adjacent the unloading end thereof, means for moving an article thereon, an elevator positioned adjacent the unloading end of the lower heating compartment, means for raising and lowering the same, means for moving the movable section to a position above the elevator, and for returning the movable section to its position in the furnace, means for holding the article in superimposed relation on the elevator during the return of the movable section, and means adjacent the loading end of the upper heating compartment for moving the articles on the elevator into the upper heating compartment.
3. A transfer mechanism for a furnace having an upper and a lower heating compartment comprising a movable section positioned in the lower furnace and adjacent the unloading end thereof, a plurality of carriers in the upper and lower heating compartments, means for moving one of the carriers onto the movable section, an elevator positioned adjacent the unloading end of the lower heating compartment, means for raising and lowering the same, means for moving the movable section and the carrier thereon to a position above the elevator, and for returning the movable section to its position in the furnace, and means for holding the carrier in its position above the elevator during the return of the movable section, and means for moving the carrier into the upper heating compartment when the elevator is in its raised position.
4. A transfer mechanism for a furnace having an upper and lower a heating compartment, com-

prising a movable guide section positioned in the lower heating compartment and adjacent the unloading end thereof, a plurality of carriers in the upper and lower heating compartments, means for moving one of the carriers onto the movable guide section, an elevator positioned adjacent the unloading end of the lower heating compartment and having movable guide means thereon longitudinally aligned with the movable guide section in the lower heating compartment, means for moving the movable guide section in the furnace and the carrier thereon to a position above the elevator, the said means at the same time moving the guide means on the elevator from the same, and for returning the movable guide section to its position in the furnace at the same time returning the guide means on the elevator to its position thereon, and means for holding the carrier in its superimposed relationship to the elevator during the return of the guide means to the furnace to permit the carrier to be engaged by the guide means on the elevator, means for raising the elevator to a position whereby the carrier is aligned with the upper heating compartment, means for moving the carrier from the 100 guide means on the elevator into the upper heating compartment, said raising means being reversible for returning the elevator to its position whereby the guide means thereon comes in longitudinal alignment with the movable guide section in said lower compartment.

5. The combination with a furnace having two heating compartments, of a plurality of carriers for supporting articles thereon unshielded from the influence of the heat in the compartments, means for causing movement of the carriers through one compartment, means at the discharge end thereof for withdrawing the loaded carrier from the compartment to permit unloading and reloading thereof, means for transferring the carriers to the adjacent end of the companion compartment, and means for causing movement of the said carriers through the second compartment.

6. The combination with a furnace having two heating compartments, of a plurality of carriers for supporting articles thereon unshielded from influence of the heat in the compartments, means for causing movement of the carriers through one compartment, means at the discharge end thereof for withdrawing the loaded carriers from the compartments to permit unloading and reloading thereof, means for transferring the carriers to the adjacent end of the companion compartment, means for causing movement of the said carriers through the second compartment, and means for returning the carriers to the loading end of the first compartment.

7. The combination with a furnace having two heating compartments, one positioned above the other, of a plurality of carriers for supporting articles thereon, means at one end of the lower heating compartment for moving the carriers therethrough, elevating means at the opposite ends of the lower heating compartment for raising the carriers to a position in longitudinal alignment with the upper heating compartment, means for moving the carriers from the elevating means through the upper heating compartment, and means adjacent the opposite end of the upper heating compartment for lowering the carriers to a position in longitudinal alignment with the lower heating compartment.

HARRY J. KUHLMAN.
